MACHINIST'S CALCULATOR

Earl H. Haviland, Baltimore, Md.

Application March 20, 1943, Serial No. 479,849

2 Claims. (Cl. 235—66)

This invention appertains to machinists' tools and more particularly to a device for giving readings in a facilitated form. It is particularly intended for use in the setting or use of equipment in the production of mechanisms. The objects of this invention include the provision of a portable instrument able to be manipulated easily to bring various lines of information or data to the attention of the user, as needed to perform various functions or processes in machine or tool work. Also to present in a mechanical manner such information customarily and conventionally printed in books or loose charts, that are hard to employ while the worker is doing his work on a machine or bench. Another object is to do certain operations of addition and subtraction of inches or parts of inches or other common scales in quick simple and interpolated manner. A further object is to provide a device that can withstand hard use in the shop; that will keep its information conveniently available and accessible under difficult conditions without difficult compilations, and which will not become damaged and unusable through ordinary use, such as by oil, dirt and dropping. A still further object is to have the device non-rolling and self indicating.

Other objects will become apparent as the invention is more fully set forth.

In the use of machines and tools by machinists and tool makers, the sizes of drills, taps, the proper index plate to be used on the head of a milling machine, the cords of various circles, the amount of taper per foot including the angle thereof, division and multiplication of decimals and other items are frequently necessary. The obtaining of such information becomes a matter of investigation through books or charts, assuming that they are available, aside from the great loss of time. The oily and dirty condition of the equipment, causes the books and charts to become soiled and damaged in a very short time. This former arrangement is also cumbersome and invites mistakes. In this invention, the use of books or loose charts is eliminated. The device is provided with the data arranged on a cylinder in straight lines, easily followed under eye holes provided in its cover. The parts are preferably made of a common plastic and are cleanable. The printing necessary for providing the information can be readily printed or impressed on this material, so as to show up clearly. Mechanism provided at one end provides a simple but effective way of deriving fractions and decimals and adding or subtracting therefrom, as well as giving audible signals of the value of the answer.

In the drawings which illustrate an example of this invention:

Figure 1 is a plan view of a machinist's calculator embodying this invention;

5 Figure 2 is a side elevation partly in section to show the operating mechanism;

Figure 3 is an end view of Figure 1;

Figure 4 is an end view of the rotating end of the device shown in Figure 1;

10 Figure 5 is a view taken along lines 5—5 of Figure 2 with the bolt 49 removed;

Figure 6 is a view taken along lines 6—6 of Figure 2;

15 Figure 7 is a view of the chart used in this device;

Figure 8 is a dismantled view of the operating end portion in perspective looking at their rear or internal faces, the parts being separated to make their construction clear;

20 Figure 9 is another view of the same parts indicated in Figure 8 looking at their front faces, in perspective;

Figure 10 is a perspective view of the cylinder body of the device;

25 Figure 11 is a perspective view of the cover used over the cylinder body, and

Figure 12 is an enlarged view of rotating end of the device partly in section.

Similar reference characters refer to similar 30 parts throughout the drawings.

In the drawings, 1 represents a cylinder consisting of a body having raised spaced ridges 2 to separate its external and peripheral surface into sections, 3 and 4. Its end portion 6 is 35 formed into a hexagon contour 7 to give it a non-rolling feature, when laid down on a horizontal surface. The opposite end portion 8 known as the adding, subtracting and decimal and fraction conversion end is centrally recessed and tapped

40 at 9 to receive a bolt having screw threads 5. A pawl 10 is supported in a slot 11 in the same portion 8 and acts on its hinge pin 12 to rotate in the longitudinal direction of the device. This pawl is preferably constructed as indicated in 45 the drawings with its engagement piece 13 formed with flattened sides 14 and beveled edges 15. The lower portion is extended at 16 to function in the manner to be described, and the hole 17 takes the hinge pin 12. The recess 18 in the portion 8 is 50 made to align the cylinder and adjacent index sleeve shield 24 that fits into it.

A revolving mechanism is mounted on the fraction adding and subtracting and decimal conversion end 8 with the peripheral surface of its bar- 55 rel registered with the peripheral surface 20 of

the cylinder end 8. The surface 19 adjacent of a flange end 29 is engraved with marks 21 used for adding or subtracting purposes. The mechanism consists of several main parts, namely the handle piece 22; the cylindrical escapement drum 23 with its notches 27; the index shield 24; the clicking washer 25 and tripper 26; a sleeve 36 and a bolt 49 having the screw threaded end portion 5 adapted to engage in the screw thread 9 and coil spring 28 for tensioning the sleeve. The washer 25 is press fitted to the end of the sleeve 36 to prevent its moving.

The handle piece 22 has an outer rim 29 extended to align with the hexagon 7 of the opposite end of the roll. It is dished at 31 and the plate 32 forming its bottom is arcuately slotted at 33 to permit inspection of the back 30 of the escapement drum 23 through a hole 38 in the shield 24 that is positioned between it and the back of the escapement drum. This escapement drum 23 has figures 34 engraved on it and adapted to show through the slot 33 and hole 38 when properly registered therewith. The escapement drum 23 is held and guided peripherally by the circular inside surface 39 that surrounds it. Internally and centrally the shield 24 is provided with a cylindrical boss 40 having a central hole 46 through it. This boss fits closely within a centrally located recess 42 in the back portion of the escapement drum 23 and serves to keep it in place and provide a bearing surface for same. The front portion of the escapement drum is recessed centrally at 43 to receive and hold the clicking washer 25. The sleeve 36 is as indicated in Figures 8 and 9 having a cylindrical pipe like portion, on which a cylindrical head 47 of larger external diameter is mounted at one end. This head is countersunk to permit the head 50 of the bolt 49 to set in flush, while the body of the latter passes through inside the sleeve with its screw threaded portion 5 projecting out, and disposed in the threaded hole 9. Externally the sleeve surface contacts with the internal surface of three parts. The internal surface of the central holes 44 of the handle piece 22; the internal surface of the hole 46 in the boss 40, and the hole 44 in the cylindrical escapement drum member 23, to act as a support for washer 25, and aligns them all with each other. The knurled enlarged head 47 of the sleeve 36 presses against the spring 28 which contacts the face of the plate 32, when in place. The passage 48 through the sleeve allows the holding element 49 to pass through it and thread into screw threads 9, while its head 50 sets in a counterbore recess 51 in the sleeve head 47. The bolt is counterbored centrally at 53 to receive a wrench used for screwing it in. The washer 25 has a bevelled trip pin ridge 26 on its face 54 large enough to strike and operate the extended portion 16 of the pawl. When the ridge 26 contacts the portion 16 it moves the pawl 13 into contact with the notch 27 of the escapement drum 23 so the latter cannot be turned with the sleeve and piece 22 for the space of one tooth and show the proper numeral 34 through hole 38 and arcuate slot 33. The coil spring 28 is disposed between the head 47 of the sleeve 36 and the face 32 of the barrel piece 22 to give the former frictional and resilient resistance.

The sections of the cylinder have light colored plastic charts 55 closely attached to the circumferential surfaces of same. The charts are preferably printed in columns A, B, C, D, E, F, 75

G, H, with data pertaining to drills, taps, decimals, fractions, chords, number of screw threads and other information. A cover 56 preferably of plastic is mounted over the cylinder as shown, and between the hexagon and handle.

This cover has its end edges 57 serrated to engage in serrations 58 on the cylinder edges. This is to control the movement of the cover thereon and prevent its slipping. The ridges 2 raise the cover off the printed forms or cards 55, and keep it from rubbing off the printing or impressed marks therefrom. Openings 60 in the cover form eye holes for each double or single column and are aligned horizontally across to permit all in a line to be read off at one reading, if desired. The titles 59 of each column are marked off on the cover to identify same easily.

The pawl however holds the notch and prevents the escapement drum from rotating while the tripper 26 rotates through the space of one notch. The spring 61 rocks the pawl 10 out of engagement with the notch as soon as the lug 26 rotates past the pawl and thereby releases it and allows the escapement drum 23 to rotate with the sleeve 36. The pawl is then dropped back into the notch following and holds the escapement drum until the sleeve and the parts operating therewith have moved around another revolution. This action is then repeated. There is sufficient friction between the sleeve and the escapement drum to permit this, when the pawl is not engaged and holding it stationary. The serrations holds the cover and barrel together, even when a little force is applied and permits one to ride on the other. This is to prevent slipping and not obstruct the turning of the cover on the barrel.

The markings of the card are preferably arranged in vertical columns with their quantities aligned on horizontal or transverse lines across the card, as indicated. The columns are listed or titled somewhat as follows:

- A (Taps and tap drills).
- B (Milling index).
- C (Cord of 1" circle).
- D (Taper per foot including the angle).
- E (Drill number).
- F (Division of decimals).
- G (Multiple decimal).

The readings are made to suit those common quantities frequently brought into use in the machine or tool shop. The horizontal figures follows each other in sequence to bring out different values, preferably related in some way to each other. This is brought out by referring to the list of numerals shown on the drawings as a separate figure.

The items on the charts are read by adjusting the cover on the cylinder until the inspection openings 60 are aligned with the line of horizontal figures selected to be read. They are read easily without confusion with those on other lines. This makes the process of getting the values quicker and more accurate. The last column 62 on the chart or card is arranged to rotate and is for a different purpose and is on the part 24. It has a series of fractions 63 and corresponding decimals 64 vertically arranged as shown. Next to the rotating card 62 is a fixed card 65 attached to the section 4 comprising a series of fractions 66 and decimals 67 which are similar to those shown on card 62. On the peripheral surface 19 of the index shield is marked a series of markings similar to the markings found on the sleeve and barrel of a micrometer and are added or subtracted in the

same way, and are arranged to add up with the series 62 and 63 above mentioned.

The card having the column 62 marked thereon is secured to the element 24 in any suitable manner, so as to turn with it. The turning of the knob 47 does this directly. Attached to the knob is a sleeve which rotates the element 24. The gear 23 is rotated by the sleeve through its frictional contact through the boss 49, and wick 71. The column 65 is secured to the body 1, and is to be considered as stationary with it.

The operation of the device is as follows:

Turn the outer rim 29 until the zero (0), on the peripheral surface 19 of the barrel 22 aligns with the mark 1.000, on the card 62 and zero (0) on the back of the escapement drum gear 23 shows through hole 38 and arcuate slot 33. The device is now ready for use. Assume that the dimensions 1", $\frac{3}{8}$ ", and $\frac{1}{16}$ " are to be added together, the procedure will be as follows: Turn the knurled head 47 one full turn until the number one (1), shows through hole 38 and slot 33 and a click is heard. The head 47 is then turned until the markings 1.000, on card 62 is aligned with the fraction $\frac{3}{8}$ " and corresponding decimal on card 65. (The zero "0" on the peripheral surface 19 of the barrel 22 should still be aligned with the mark 1.000 on the card 62.) With this setting the user of the device glances up the column of figures on the card 62 until he reaches the fraction $\frac{1}{16}$ ". Opposite this he will find the total of the fraction to be $\frac{7}{16}$ " which plus the one inch (1") will be showing through the hole 38 and slot 33, making a total of $1\frac{7}{16}$ ".

If the user wishes to subtract a fraction or decimal he proceeds as follows: Take as an example $1\frac{7}{16}$ " minus $\frac{1}{32}$ ". The setting will remain the same as above and the operator will find $\frac{1}{32}$ " on the card 62 to be opposite $\frac{7}{16}$ " on card 65. The answer is $1\frac{3}{16}$ " or 1.40625. By this method a fraction or decimal can be added or subtracted from each other. In the event it is desired to subtract $\frac{1}{16}$ " from $\frac{7}{16}$ ", the procedure will be as follows: Align the $\frac{1}{16}$ " mark on the card 62 with the $\frac{7}{16}$ " mark on the card 65, glance down card 62 until you reach the mark 1.000, and opposite you will find the answer to be $\frac{3}{8}$ ".

When the addition rises above unity, then the tripper 26 of the washer 25 will come into contact with the lower portion 16 of the ratchet pawl 10 and forces the engagement piece 13 between the notch 27. This holds the escapement drum fixed to the cylinder and allows the hole 38 and slot 33 to slip over the escapement drum until a new member shows up in the slot and hole. The lower portion 16 of pawl 10 contacts the face 54 of the washer 25 through the operation of spring 61 and withdraws the engagement piece 13 from contact with the notch and allows the escapement drum to rotate free of the fixed cylinder until a complete revolution has been made. You can reverse the operation and subtract whole numbers.

If the fractions add up to two inches 2" plus a fraction or decimal, the back of the escapement drum will show (2) through the hole 38 and slot 33 in the same manner. The bolt 49 and its incidental parts will fasten in place as indicated in the drawings. The escapement drum is given adjustable frictional resistance by the screw 70 and frictional insert 71 as it presses on the cir-

cumferential surface of the sleeve 36. The screw 70 is operated from the periphery of the escapement drum 23 and index shield 24 by inserting a screw driver in the counterbored hole 72 in the escapement drum and hole 73 in the index shield.

While but one general form of the invention is shown in the drawings and described in the specifications, it is not desired to limit this application to this particular form or in any other way otherwise than limited by the scope thereof, as it is appreciated that other forms could be made that would use the same principles and come within the scope of the appended claims.

Having thus described the invention what is claimed is:

1. In combination, a body, a revolving mechanism associated therewith comprising, a barrel piece with an enlarged flanged end for manual operation thereof, an index shield disposed against the said barrel piece, a toothed drum rotatably mounted in the shield normally rotatable therewith, said drum having indicia thereon for display through an aperture in the shield, means for holding said element against the body and rotatably supporting them, a pawl mounted in the body normally free of the toothed drum and adapted when actuated to lock the toothed drum momentarily against rotation, means to actuate the pawl once for each revolution of the index shield, means in the barrel piece for displaying a given value on the toothed drum which has been positioned at the aperture in the index shield, the rotation of the elements being correlated with a second set of indicia on the index shield, a set of indicia on the body and markings on the barrel piece.

2. In combination with the body of a device of the class described, a revolvable mechanism comprising in combination, a bolt secured to the body and extending axially therefrom, a sleeve mounted on the bolt and rotatable thereon, a cam fastened to an end of the sleeve adjacent the body, a toothed drum rotatably mounted on the sleeve, a pawl mounted in the body normally free of the toothed drum and adapted to be actuated by the cam once for each revolution of the latter to cause the pawl to momentarily engage the toothed drum and lock it against rotation while so engaged, indicia on the outer face of the toothed drum, an index shield having a cylindrical surface with indicia thereon rotatably mounted on the sleeve and having a display aperture in its end for display of a selected value on the toothed drum, a barrel piece rotatably mounted on the sleeve and provided with an end flange for manual operation thereof and having an extended aperture in its end for allowing the aperture in the index shield to be displayed therein, a spring mounted on the sleeve between the barrel piece and a head on the outer end of the sleeve, indicia on the cylindrical surface of the body and index shield, respectively, the indicia on all the elements being so correlated that the fractional portion of a sum, in addition, will be displayed on the body and the whole portion on the toothed drum, which whole portion will be displayed through the aligned display apertures in the index shield and barrel piece.
